(57) **CLAIM**

We claim the ornamental design for a dish rack, as shown and described.

DESCRIPTION

FIG. 1 is a front perspective view of one embodiment of a dish rack of the present disclosure;

FIG. 2 is a rear perspective view of the dish rack of FIG. 1; FIG. 3 is a front elevational view of the dish rack of FIG. 1; FIG. 4 is a rear elevational view of the dish rack of FIG. 1; FIG. 5 is a first side elevational view of the dish rack of FIG. 1;

FIG. 6 is a second side elevational view of the dish rack of FIG. 1;

FIG. 7 is a top plan view of the dish rack of FIG. 1;

FIG. 8 is a bottom plan view of the dish rack of FIG. 1; FIG. 9 is a front perspective view of another embodiment of a dish rack of the present disclosure;

FIG. 10 is a rear perspective view of the dish rack of FIG. 9;

FIG. 11 is a front elevational view of the dish rack of FIG. 9;

FIG. 12 is a rear elevational view of the dish rack of FIG. 9; FIG. 13 is a first side elevational view of the dish rack of FIG. 9;

FIG. 14 is a second side elevational view of the dish rack of FIG. 9;

FIG. 15 is a top plan view of the dish rack of FIG. 9; and, FIG. 16 is a bottom plan view of the dish rack of FIG. 9.

Broken lines are environmental only and form no part of the claimed design.

1 Claim, 8 Drawing Sheets
